UNITED STATES PATENT OFFICE.

WILLIAM C. ANDERSON, OF TOLEDO, OHIO.

DESIGN FOR THE ORNAMENTATION OF GLASSWARE.

SPECIFICATION forming part of Design No. 20,921, dated July 7, 1891.

Application filed June 15, 1891. Serial No. 396,395. Term of patent 3½ years.

To all whom it may concern:

Be it known that I, WILLIAM C. ANDERSON, of Toledo, county of Lucas, and State of Ohio, have invented a certain new and original Design for the Ornamentation of Glassware; and I do hereby declare that the following is a full, clear, and exact description of the invention, which will enable others skilled in the art to which it appertains to make and use the same, reference being had to the accompanying drawings, and to the figures of reference marked thereon, which form part of this specification.

The class to which this design relates is that of ornamentation of glassware; and the design pertains to the ornamentation of the exterior surface thereof.

The drawings represent in Figure 1 a bottom plan view of a dish containing the design, and in Fig. 2 a transverse section on lines *x*, Fig. 1.

The design is applicable to any kind of glassware, such as bowls, plates, jugs, and dishes.

The leading features of my design are radial prisms with obovate prisms eccentric to the center of the dish, whereby there are formed radial cuneal planes, in which are checkering and hexagonal planes embellished with a central stud and a prismatic border. From the center 1 of the dish there are radial prisms 2, extending therefrom to the hexagonal border 3, the radial prisms being crossed by a series of obovate prisms 4, arranged eccentrically to the center 1, the point 5 of each extending to the border. The radial prisms are arranged

in series, comprising the two outer prisms 6, extending from the center to the border, and four prisms 7, arranged in pairs and extending in parallel relation with the outer prism, 40 whereby there is formed a cuneal plane 8, embellished with miniature prisms 9, crossing at obtuse angles, the diamond spaces formed thereby being embellished with a checker- 45 ing. Between each series of radial prisms is a cuneal space 10, crossed by the obovate prism, thereby forming hexagon 11, having a central 50 stud 12, with a block bordering and a many-pointed star, the hexagon being crossed by tangential lines 13, thereby forming prismatic 55 studs 14. The border is of an irregular scallop alternating with the projections of the cuneal planes 10, which project above the regular surface of the edge, and are embellished with acute-angled prisms and checker- 60 ing. The ornamentation herein described harmonizes with the shape of the dish and gives a pleasing symmetry to the same.

What I claim is—

The design for the ornamentation of glass- 60 ware herein described and shown, consisting of the radial prisms, the obovate prisms forming hexagons, and the embellishment thereof, as set forth.

In testimony that I claim the foregoing as 65 my own I hereby affix my signature in presence of two witnesses.

WILLIAM C. ANDERSON.
